UNITED STATES PATENT OFFICE.

JAMES F. HINES, OF CLEVELAND, OHIO, ASSIGNOR, BY DIRECT AND MESNE ASSIGNMENTS, OF ONE-THIRD TO JOHN M. SARVER AND ONE-THIRD TO JOSEPH K. BYE, BOTH OF COLUMBUS, OHIO.

CURTAIN-POLE.

1,278,346.

Specification of Letters Patent. Patented Sept. 10, 1918.

Application filed October 4, 1915. Serial No. 53,917.

To all whom it may concern:

Be it known that I, JAMES F. HINES, a citizen of the United States, residing at Cleveland, in the county of Cuyahoga and 5 State of Ohio, have invented certain new and useful Improvements in Curtain-Poles, of which the following is a specification.

The invention relates to poles for hanging curtains at the top of a window or elsewhere, and the object of the improvement is 10 to provide a pivotal support for one end of the pole which permits the curtain to be uniformly draped without obstruction from end to end of the pole, and also permits the 15 pole with the curtain thereon to be swung on its pivoted end away from the window without binding or bunching the curtain or impinging the window frame at the pivoted end of the pole.

20 These objects and other advantages are attained by the construction and arrangement illustrated in the accompanying drawing, forming part hereof, in which—

Figure 1 is a fragmentary face elevation 25 of a window top showing the improved pole mounted thereon;

Fig. 2, a similar elevation showing the pivoted end of the pole, with the pivotal support in section;

30 Fig. 3, a detached perspective view of the pivotal support;

Fig. 4, a detached side elevation of the keeper for the free end of the pole;

Fig. 5, a fragmentary plan view showing 35 the pivotally supported end of the pole;

Fig. 6, a fragmentary face elevation of the top of a window showing a pair of poles pivotally supported, one at each side thereof; and

40 Fig. 7, a face elevation showing a modified form of the pole bracket.

Similar numerals refer to similar parts throughout the drawings.

The pivotal support 1 for the curtain pole, 45 includes the supporting bracket 2 secured to one side of the window frame, and the pole bracket 3 secured on one end of the curtain pole.

The supporting bracket is preferably 50 formed with the base plate having ears on each side with slots or apertures 6 therein, for securing the bracket to the side of the window by means of the screws 7.

The supporting bracket is also formed 55 with the forwardly extending shank 8 which

is made of sufficient vertical depth to rigidly sustain the supporting head 9 which is formed on the forward end of the stem.

The vertical journal bearing or socket 10 is formed in the head of the supporting 60 bracket and is made of such a substantial length as will securely support the pivot stem 11 of the pole bracket.

The pole bracket is formed with the pendant pivot stem 11 which is made to neatly 65 fit and rotate in the journal bearing 10 in the supporting head, and at the upper end of the pivot stem is formed the annular shoulder 12 adapted to bear and rotate upon the upper end 13 of the supporting head. 70

The body 14 of the pole bracket is formed with a relatively short arm 15 or 15^a on one side of the pivot stem and with the relatively long arm 16 on the other side of the pivot stem; which arms are respectively adapted 75 to engage and support one end of the curtain pole 17.

The short arm of the pole bracket is provided with a cylindric socket 18 or 18^a adapted to receive and engage the end portion of 80 the curtain pole 17. This arm is preferably made in a semi-spherical form 15, thus closing the end of the curtain pole and forming a round smooth end for the curtain bracket so as not to catch the curtain, as shown in 85 Figs. 1, 2, 3, 5 and 6 of the drawings.

This short arm may be formed as a ring 15^a wherein the cylindric socket 18^a is a through opening, through which the curtain pole may extend at one end, as shown in Fig. 90 7, of the drawings. In this case it is preferred to provide a suitable finishing cap 19 for the protruding end of the curtain pole.

The body portion 14 and long arm 16 of 95 the pole bracket are cylindrically concaved on their upper side, coaxial with the cylindric socket formed in the short end thereof, thus forming a supporting seat for a considerable portion of the curtain pole extending a substantial distance along the under side thereof from the pivot axis of the pole bracket.

The top and sides of the body portion and long arm of the pole bracket are cut away 105 so as to freely expose the sides and the top of the curtain pole, excepting only the extreme end thereof which is entered and secured in the cylindric socket in the short arm of the bracket. By this formation of 110

- the bracket it is evident that a curtain may be uniformly draped upon the pole throughout its entire length without being obstructed or interfered with by the pole bracket.
- 5 A suitable aperture 20 is preferably provided in the end of the long arm of the bracket, through which aperture a screw 21 may be passed for securing the pole in the seat and socket formed by the pole bracket.
- 10 The parts are so proportioned and arranged that the extreme length of the short arm of the pole bracket is only about half the length of the shank of the supporting bracket, as shown in broken lines in Fig. 5, so that the free end of the pole can be rotated directly outward without any portion of its pivotal bracket impinging the frame of the window; and it is also evident that a curtain may be draped over and beyond the
- 15 extreme end of the pole and its pivotal bracket, and made fast to the window frame without being bunched or crushed against the window frame when the free end of the pole is swung away therefrom.
- 20 25 The long arm of the pole bracket is extended a substantial distance along the under side of the pole to give sufficient leverage, with reference to the end of the pole which is secured in the short arm of the bracket, so as to firmly sustain the free end of the pole from sagging, excepting as the pole may bend from its own elasticity. Such an extension of the long arm of the pole bracket is made to compensate for the necessity of making the other arm short enough to permit the bracket and the curtain draped thereover to swing inward without impinging or bunching against the window frame.
- 30 35 The cylindric seat in the pole bracket is preferably inclined upward from the short arm to the long arm thereof, with reference to the vertical axis of its pivot stem, as shown more clearly in Fig. 2, so as to compensate for any bending there may be in the body and free end of the pole by reason of its elasticity, or any looseness there may be in the pivotal bearing; and it is evident that by this construction the free end of the pole will always be maintained at the same height as the pivoted end thereof.
- 40 45 50 A suitable keeper 22 may be secured to the opposite side of the window frame for normally receiving and holding the free end of the curtain pole from swinging away from the window, and it is preferred to use such a keeper when a single pole is used extending entirely across a window, as shown in Fig. 1, but the use of such a keeper is not

usually necessary where a pair of comparatively short poles are pivoted, one on each side of a window, as shown in Fig. 6.

I claim:

1. A pivotal support for the end of a curtain pole including a supporting bracket adapted to be secured to a window frame 65 or the like and having a shank with a head thereon spaced from the frame, and a pole bracket having a pendent stem pivoted on the supporting head with a relatively short arm engaging one end of the curtain pole 70 and a relatively long arm forming a seat for the curtain pole extending a substantial distance along its under side from the axis of the pivot stem.

2. A pivotal support for the end of a curtain pole including a supporting bracket adapted to be secured to a window frame or the like and having a shank with a head thereon spaced from the frame, and a pole bracket having a pendent stem pivoted on 80 the supporting head with a relatively short arm engaging one end of the curtain pole and a relatively long arm forming a seat for the curtain pole extending a substantial distance along its under side from the axis of 85 the pivot stem, the shank of the supporting bracket being longer than the short arm of the pole bracket.

3. A bracket for a curtain pole comprising a pendent pivot stem, a relatively short arm 90 engaging one end of the curtain pole and a relatively long arm forming a seat for the curtain pole extending a substantial distance along its under side from the axis of the pivot stem, the short arm of the pole bracket 95 having a socket for inclosing the end of the curtain pole and being shaped semi-spherical externally so as not to catch the curtain.

4. A bracket for a curtain pole comprising a pendent pivot stem, a relatively short arm 100 engaging one end of the curtain pole and a relatively long arm forming a seat for the curtain pole extending a substantial distance along its under side from the axis of the pivot stem, the seat in the pole bracket being 105 inclined upward from the short arm to the long arm thereof with reference to the vertical axis of the pivot stem.

5. A bracket for a curtain pole comprising a pendent pivot stem, a relatively short arm 110 engaging one end of the curtain pole, and a relatively long arm forming a seat for the curtain pole and extending a substantial distance along its under side from the axis of the pivot stem.

JAMES F. HINES.
